UNITED STATES PATENT OFFICE.

HENRY ADOLPH CLAUSING, OF LIMA, OHIO.

PIANO ATTACHMENT.

Application filed June 10, 1922. Serial No. 567,344.

To all whom it may concern:

Be it known that I, HENRY A. CLAUSING, a citizen of the United States, residing at Lima, in the county of Allen and State of Ohio, have invented a new and useful Piano Attachment, of which the following is a specification.

This invention aims to provide a simple means whereby a solo note may be brought out in the operation of a player piano, it being possible to control the accentuation of the solo note, and also to control the accompaniment, the device being intended to be used with a special perforated music sheet, but being so constructed that it may be used with an ordinary music sheet, commonly known as an 88 note sheet.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the drawings:

Figure 1 shows in section a device constructed in accordance with the invention; Figure 2 is a fragmental elevation wherein parts are broken away; Figure 3 is a section on the line 3—3 of Figure 1; Figure 4 is a section on the line 4—4 of Figure 1; Figure 5 is a section through the suction casing and attendant parts; Figure 6 is a plan showing a portion of the music sheet.

In carrying out the invention, there is provided a frame 1 which may be disposed in any desired position in the piano, the showing of Figure 1 being to some extent diagrammatic. For convenience in assembly and repair, the constituent parts of the frame 1 may be held together by bolts 2. A main suction chamber 3 exists in the frame 1 and communicates through a port 4 with a casing 5 on the frame 1, suction being created in the casing by any suitable means, designated by a pipe 6.

First pneumatics 7 and second pneumatics 8 are located in the suction chamber 3 and are mounted on the frame 1, the pneumatics

having bleed ports 9 which communicate with the chamber 3. A passage 10 is formed in the frame 1 and is located at the side of the chamber 3. A passage 11 is formed in the frame 1 and is located by the side of the passage 10. A port 12 establishes communication between the passage 10 and the suction casing 5. A port 14 establishes communication between the passage 11 and the suction casing 5. A valve 15 controls the port 12 and is mounted on the casing 5. A similar valve 16 controls the port 14. The valves 15 and 16 may be operated from a remote point by any suitable means indicated at 17.

Passages 18 and 19 are formed in the frame 1 and are disposed at right angles to the passages 10 and 11. Ports 20 connect the passage 10 with the passages 18. Ports 21 connect the passage 11 with the passages 19. Chambers 22 are formed in the frame 1 and communicate with adjacent passages 18 and 19. Ports 23 in the casing connect the passages 19 with the chambers 22. Ports 24 connect the passages 18 with the chamber 22. The frame 1 has an exhaust opening 25 leading from the chamber 22. Striking pneumatics 26 are mounted on the frame 1. Channels 27 lead from the striking pneumatics 26 to the chambers 22. A valve 28 controls the port 24. A valve 29 controls the port 23 and the exhaust opening 25 at different times. The valves 28 and 29 have stems 30 mounted in bridges 31 on the frame, the stems of the valves extending into the suction chamber 3 and being located in the path of the pneumatics 7 and 8.

The numeral 32 marks a tracker bar having apertures 33, 34 and 35. The numeral 36 marks a support, both the support and the tracker bar being located as desired in the piano casing. The support 36 has apertures 37, 38 and 39. A tube 40 connects the aperture 33 in the tracker bar with the aperture 37 in the support. A tube 41 extends between the apertures 34 and 38. The apertures 35 and 39 are connected by a tube 42. A movable member, such as a slide 43, is connected at 44 to the support 36 for adjustment transversely thereof. The slide 43 has apertures 45 and 46. The aperture 45 in the slide is adapted to communicate with the aperture 38 in the support 36, and the aperture 46 in the slide is adapted to communicate with the aperture 39 in the support. The aperture 45 in the slide may be

brought into registration with the aperture 37 in the support 36, the apertures 38, 39 and 46 then being closed. A flexible tube 47 connects the aperture 46 of the slide with the pneumatic 7. A flexible tube 48 connects the aperture 45 of the slide 43 with the pneumatic 8.

The device may be used with a special music sheet 49 having elongated openings 50 and smaller openings 51. In Figure 6, the numeral 52 marks an accompaniment opening.

Suppose that the valve 29 is closed with respect to the port 23, the valve 28 being closed with respect to the port 24, the striking pneumatic 26 being expanded, because air can enter the pneumatic 26 by way of the opening 25, the chamber 22 and the channel 27. Suction created through the pipe 6 in the casing 5 will be transmitted through the port 12, the passage 10 and the port 20 to the passage 18, the valve 28 being held closed by suction. Suction in the casing 5 will be transmitted through the port 14, the passage 11 and the port 21, to the passage 19, the valve 29 being held closed on the port 23 by suction. Suction in the casing 5 will be transmitted through the port 4 to the chamber 3, the air being exhausted from the pneumatics 7 and 8, through the ports 9, the pneumatics 7 and 8 being collapsed, and being retracted with respect to the stems 30 of the valves 28 and 29. Assuming that the slide 43 is in the position of Figure 1, the aperture 37 in the support 36 is closed by the slide 43, but the aperture 46 in the slide registers with the aperture 39 in the support, the aperture 45 in the slide registering with the aperture 38 in the support. Assume that the sheet 49 is traversing the tracker bar 32. The opening 51 in the sheet 49 registers with the aperture 35 in the tracker bar at the same instant that the forward end of the opening 50 in the sheet registers with the aperture 34 in the tracker bar, and the striking pneumatic 26 receives a double portion of suction, the result being that a solo note is accentuated.

Air rushes into the pneumatic 8 through a conduit comprising the opening 50 in the sheet 49, the aperture 34 in the tracker bar 32, the tube 41, the aperture 38 in the support 36, the aperture 45 of the slide 43, and the flexible tube 48. Air rushes likewise into the pneumatic 7 through a conduit comprising the opening 51 in the sheet 49, the aperture 35 in the tracker bar 32, the tube 42, the aperture 39 of the support 36, the aperture 46 of the slide 43, and the flexible tube 47. When the pneumatic 7 expands, the pneumatic, cooperating with the stem of the valve 28, opens the valve with respect to the port 24. When the pneumatic 8 expands, the said pneumatic, cooperating with the stem of the valve 29, moves the valve 29 to open position with respect to the

port 23 and to closed position with respect to the exhaust opening 25. The striking pneumatic 26 now closes, suction being created in the pneumatic, from the chamber 22, through the channel 27. Suction is brought about in the chamber 22, from the casing 5, by a double line, one branch of which comprises the port 12, the passage 10, the port 20 and the passage 18, the other branch comprising the port 14, the passage 11, the port 21 and the passage 19. Thus, the striking pneumatic 26 will respond to an increased suction, thereby to provide an accentuated or solo note. The increment of force imparted to the striking pneumatic 26 by the operation of the pneumatic 7 will be short in duration and will exist at the beginning of the sounding of the note only, because the opening 51 in the sheet 49 is small and registers with the aperture 35 in the tracker bar 32 for an instant only, whereas the opening 50 in sheet 49 is larger than the opening 51 in the sheet, the opening 50 being of any desired length and registering with the aperture 34 in the tracker bar 32 for a longer period. The suction through the port 23 may be regulated by means of the valve 16, and the suction through the port 24 may be regulated by the valve 15, the operator always having at his command, means for regulating the force wherewith the note is struck. An accompaniment note is produced by the opening 52 in the sheet 49, this opening coacting with the aperture 34 of the tracker bar 32. The accompaniment note may be regulated as to the force with which it is struck, through the medium of the valve 16, but, assuming that there is no opening in the sheet, adjacent to the opening 52, and corresponding to the opening 51, the accompaniment note will not be brought out like the solo note, the pneumatic 7 remaining idle. Should there be an opening adjoining the opening 52 in the roll or sheet, and corresponding to the opening 51, then, of course, the accompaniment note may be brought out like the solo note. Although the solo note and the accompaniment note have been alluded to in the singular number, it is obvious that a chord may be produced either in the solo part or in the accompaniment part, this being a matter resulting merely from the formation of the desired number of openings in the music sheet. Should it be desired to use the ordinary 88 note sheet, the slide 43 is moved until the apertures 45 and 37 register, the apertures 46, 39 and 38 being closed, air entering the pneumatics 8 through the tube 48, the aperture 45, the aperture 37, the tube 40 and the aperture 33 in the tracker bar 32.

The general construction of the device is such that a common 88 note sheet may be used interchangeably with a sheet of special

construction. Solo notes may be brought out, and the force wherewith either solo notes or accompaniment notes are struck, may be regulated, it being possible also to regulate the force used in striking a note when the note is produced from the ordinary 88 note sheet.

What is claimed is:—

1. In a device of the class described, a suction means, a chamber provided with an outlet, a single striking pneumatic communicating with the chamber, conduits leading from the suction means to the chamber, pneumatics having bleed-ports communicating with the suction means thereby to effect a collapsing of the last-specified pneumatics, valves controlling the conduits and operated by the last-specified pneumatics, one valve controlling the outlet, both valves being responsive to suction, when the last-specified pneumatics are collapsed, to cut off suction through the conduits and to cause said one valve to open the outlet, separate air-admission means for the last-specified pneumatics, and a tracker having separate apertures communicating with the respective air-admission means, thereby to expand the last-specified pneumatics, to close said one of the valves with respect to the outlet, and to open both valves with re-

spect to the suction conduits and the chamber thereby providing an increased suction on the striking pneumatic.

2. A device of the class described, constructed as set forth in claim 1, and further characterized by the provision of separate valves under the governance of an operator and controlling adjustably the amount of suction through each conduit upon the chamber. 35

40

3. A device of the class described, constructed as set forth in claim 1, and further characterized by the fact that the tracker has another aperture, and a movable member having ports communicating with the air-admission means and with the first-specified apertures in the tracker, said member being movable to place in communication with said other aperture in the tracker, that one of the air-admission means which operates with that one of the last-specified pneumatics which operates said one valve. 45

50

In testimony that I claim the foregoing as my own, I have hereto affixed my signature in the presence of two witnesses.

HENRY ADOLPH CLAUSING.
